PIUS L. SHEPLER AND SAMUEL L. IRWIN, OF WHITEHOUSE, OHIO.

Letters Patent No. 83,218, dated October 20, 1868.

IMPROVEMENT IN WASH-BOILERS.

The Schedule referred to in these Letters Patent and making part of the same.

To whom it may concern:

Be it known that we, PIUS L. SHEPLER and SAMUEL L. IRWIN, of Whitehouse, in the county of Lucas, and State of Ohio, have invented a new and useful Improvement in Apparatus for Washing Clothes; and we do declare that the following is a true and accurate description thereof, reference being had to the accompanying drawings, and to the letters of reference marked thereon, and being a part of this specification.

Figure 1 is a perspective view of an ordinary boiler, commonly used for washing-purposes, provided in part with our improvement.

Figure 2 is a plan view of our grated false bottom.

Figure 3, a view of our sleeved connecting and distributing-pipe.

Like letters indicate like parts in each figure.

This invention is designed to reduce the labor required by ordinary processes of washing clothes, and consists in so constructing a boiler and its attachments that, when properly filled, and acted upon by fire or heat, a vacuum will be created below the false bottom, by a displacement of the water, which is forced to ascend in the chambers at the ends of the boiler, and thence passing into suitable distributing-tubes, is discharged, in a constant and steady shower, upon the clothes, and, forcing its way down through the same, abstracts the dirt in its passage; or, in other words, the apparatus is designed to keep a constant current of water passing through the clothing being operated upon.

We construct a boiler, A, provided with chambers B, at each end of and outside the wall of the boiler. These chambers may be semi-circular in form, or any other desired shape, and should be larger at the bottom than at the top. A slot should be cut through the

walls of the boiler, at either end, affording an outlet from the boiler into the chambers, near their bottoms, which rest upon and are attached to ears C, which form a continuation of a pit-bottom of the boiler. The upper ends of these chambers terminate in tubes D, projecting inward through the end walls of the boiler, and, when in operation, are connected by two perforated tubes E, one of which is slipped inside the other telescopically. Across the pit in the bottom of the boiler are rigidly fastened braces F, which also act as a foundation, upon which rests the grated false bottom J, which is held in place by button G, which engages with catches or legs H, soldered or riveted to the side walls of the boiler. I is a suitable faucet inserted through the wall of the boiler, below the false bottom, for the purpose of enabling the operator to draw off filthy water at pleasure.

What we claim as our invention, and desire to secure by Letters Patent, is—

The perforated sliding extension tube E, in combination with the chambers B, the grated false bottom J, provided with button G, and the lugs H, on the boiler A, substantially as and for the purposes set forth.

Also, the ears C, in connection with the chambers B, and the pit-bottom of the boiler A, substantially as described.

And the combination of all the above-named parts with the faucet I, when arranged and operating substantially as and for the purposes herein specified.

PIUS L. SHEPLER.
SAMUEL L. IRWIN.
